INVENTOR

Gerard R. Marsico.

UNITED STATES PATENT OFFICE.

GERARD R. MARSICO, OF BROOKLYN, NEW YORK.

DESIGN FOR AN AUTOMOBILE-HORN CASING.

55,294.

Specification for Design.

Patented May 25, 1920.

Application filed February 27, 1920. Serial No. 361,655. Term of patent 14 years.

To all whom it may concern:

Be it known that I, GERARD R. MARSICO, a citizen of the United States, residing at Brooklyn, in the county of Kings and State of New York, have invented a new, original, and ornamental Design for Automobile-Horn Casings, of which the following is a specification, reference being had to the accompanying drawings, forming part thereof.

Figure 1 is a side view of an automobile horn casing, showing my new design.

Fig. 2 is a rear elevation thereof and, Fig. 3 is a front elevation of the same.

I claim:

The ornamental design for an automobile horn casing as shown.

GERARD R. MARSICO.
